UNITED STATES PATENT OFFICE.

WILLIAM BENNETT, OF TEMPE, NEAR SYDNEY, NEW SOUTH WALES, AUSTRALIA, AS-
SIGNOR OF TWO-THIRDS TO GEORGE ROCKLEY AND ALBERT CHALLEN, BOTH OF
BEXLEY, NEAR SYDNEY, NEW SOUTH WALES, AUSTRALIA.

HORN AND/OR TONE BOX FOR TALKING MACHINES, WIRELESS LOUD SPEAKERS,
AND THE LIKE.

Application filed May 22, 1925, Serial No. 32,088, and in Australia June 26, 1924.

This invention has been specially devised to provide a horn and/or tone box or "amplifier" for talking machines, wireless loud speakers and other like sound distributers which will emit sounds and tones, say of the voice, music, and the like clearly and of considerably increased and richer volume and without the vibration and distortion generally present in such apparatus heretofore and further which is comparatively cheap and of strong and of lasting construction.

This improved horn and/or tone box has an ordinary body or a shell of sheet metal pressed, stamped out, or otherwise made of the required configuration which is preferably that of a downwardly curving trumpet and according to this invention the inside of the shell or body is worked to an extremely smooth surface and has curved joinings so that it presents no angles or obstructions to sound passage therethrough, and the outside of said body or shell is coated or covered with a more or less resilient substance or material adapted to be wrapped or laid or spread or cast or moulded on the metal and this to be of graduated or tapering thickness and which said "dampen coating" as it will hereinafter be termed must be capable of dampening vibrations of sounds whose waves strike or impinge upon the inside smooth face of said body or shell and also be capable of more or less effectively preventing metallic ring in said body or shell.

After much trouble and experiment I have ascertained that the substances and materials best suited for the purposes of the desired wrapping or coating on the outside of the metal horn are compositions of plaster of Paris and pitch and compositions containing sand intermixed with sawdust, cow hair and glue and with or without wire reinforcement and I have successfully used rubber, compressed paper, cardboard and felt.

The substance or material may be cast, plastered, spread, wrapped or laid upon the body or shell in one thickness or in more or less thin layers fastened to the shell together by glue or other adhesive and preferably the depth or thickness of the so formed outer dampen-coating tapers from the smaller end of the body or shell where it is thickest owing to the sound vibrations being there the heaviest to its thinnest part at

the inlet end or mouth whereat sound vibrations are much diminished.

But in order that this invention may be readily carried into practical effect the same will now be described with reference to the drawings accompanying and forming part of this complete specification.

Fig. 1 is a plan, Fig. 2 is a front view and Fig. 3 is a longitudinal sectional elevation respectively of this improved horn and/or tone box specially constructed for a talking machine.

The body or shell 4 of this improved horn and/or amplifier is of sheet metal say galvanized or black sheet iron of suitable gauge according to the length thereof although 24 to 26 gauge has been found most satisfactory for ordinary purposes and it is made with configuration similar to that of a curved trumpet but of oblong cross section and made with soldered or pressed, curved and smoothed joints and with or without a wire reinforcement say of light wire around the outside and preferably soldered to the shell. The inside face of said shell 4 is either varnished, enamelled or plated or lacquered or otherwise more or less perfectly smoothed so as to present an unobstructed area to sound waves impinging thereupon and the outside of said shell 4 has a wrapping or coating 5 possessing the qualities hereinbefore set forth and hereinafter fully defined.

In a preferred application of the dampen-coating 5 after the outside of the shell 4 is painted varnished or enamelled (which is preferred) with several coats to prevent rusting and also to make a base course a heavy coat of sawdust is spread thereon before the last coat of paint or varnish is dry, and upon this foundation the composition of plaster of Paris, liquid glue and cow hair is laid. The preferred composition consists of by weight:—

24 parts of plaster of Paris,	100
6 parts of cow hair,	
1 part of glue,	
2 parts of water,	

mixed together to ordinary plaster consistency and it is cast or plastered on to the shell surface of the tapering thickness or thereabouts before mentioned.

In another application of the dampen-coat-

ing 5 the outside of the shell 4 is first painted or varnished to prevent rusting and is coated or covered with a film of rubber solution namely uncured rubber dissolved in benzine 5 and naptha and upon this foundation sheets of unbaked rubber are piled being cemented with the mentioned rubber solution on the foundation and one over the other until there is a complete coating 5 tapering in thickness 10 from say half an inch at the small end of the shell 4 to about one-eighth of an inch at the mouth end. But if desired this coating may be made up of repeated applications of one over the earlier of sheets of cured 15 rubber fastened to the foundation and to each other by the rubber solution so as to build up the outer wall 5 to required thickness.

In another application of the dampen-coating after the first rust resisting coating of the outside of the shell 4 has been applied instead of sheets of rubber layers of compressed paper preferably blotting paper or of cardboard or of felt or of such like are glued to the shell 4 and piled one on the earlier to one another to make up the requisite thickness of said dampen-coating 5 which then may be externally finished by paint or the like.

It is preferred that this improved dampen-coated horn should be connected to the source or intake of the sound to be distributed by means of a tapered thimble or tube 6 so that to the sound there will be less obstacle than heretofore to its spread or divergence and said sound will have less force of attack on the inside face of the horn. This thimble 6 is say of wrought or cast iron copper or brass or some other metal but is preferably 40 made of metal of sonorous quality and said

sleeve is positioned in the intake end of the inner tube 4 and retained therein by soldering or is otherwise affixed.

The horn and/or tone box 4-5 so constructed as before described is fastened in 45 place in a talking machine cabinet as ordinarily by wooden cleats or screws or other fastening devices.

In use the sound from the talking machine or amplifier diaphragm and the like enter 50 the tone horn 4-5 through the sleeve 6 which directs the sound waves forwardly in a more or less spreading or diverging stream and as said waves impinge upon the inside face of shell 4 which being inwardly smooth does not 55 offer any resistance thereto any vibrations and/or distortion of said sound are dampened and more or less absorbed by the resilient wrapping or coating 5 on the shell 4 and any metallic ring in or of the shell 4 is more 60 or less prevented and the sound issuing from the horn is considerably clarified and freed from vibration and distortion and as well increased in volume.

What I claim as my invention and desire 65 to secure by Letters Patent is:—

1. An improved horn or the like for the purposes set forth, having an inner metal shell and an outer covering therefor tapering in thickness from the inlet-end toward 70 the outlet-end, said covering being of a sound-absorbing substance.

2. A horn or the like for the purposes set forth, having an inner metal shell and an outer covering therefor of a sound-absorbing 75 substance consisting of a mixture of plaster of Paris, cow hair and glue.

In testimony whereof I have signed my name to this specification.

WILLIAM BENNETT.
